WHIPSTOCKING SLEEVE FOR DRILLABLE LINERS

Vernon V. Shepherd and Orlo R. Peugh, Long Beach, Calif., assignors to Lane-Wells Company, Los Angeles, Calif., a corporation of Delaware

Application January 2, 1940, Serial No. 312,010

2 Claims. (Cl. 255—1.6)

Our invention relates to whipstocks for drillable liners. Among the objects of our invention are:

First, to provide a whipstock which is incorporated in and lowered with a drillable liner so that when the liner is subsequently drilled up the bit will be deflected to one side;

Second, to provide a whipstock of this type which is in the form of a sleeve interposed in the drillable liner;

Third, to provide a whipstock of this type which is particularly applicable when it is desired to set a standard or steel liner and interpose a drillable section between the steel liner and the casing above, so that the standard liner below may be sidetracked; and

Fourth, to provide, on the whole, a novelly constructed whipstock which is particularly simple and economical of manufacture.

With the above and other objects in view, as may appear hereinafter, reference is directed to the accompanying drawing, in which:

Figure 1 is a diagrammatical view illustrating one manner in which our whipstock may be used;

Figure 2 is another diagrammatical view showing the manner in which our whipstock deflects the newly drilled hole from the previous bore;

Figure 3 is an enlarged fragmentary, longitudinal sectional view taken substantially through 3—3 of Figure 8; and

Figures 4, 5, 6, 7 and 8 are transverse sectional views taken through 4—4, 5—5, 6—6, 7—7 and 8—8, respectively, of Figure 1, to illustrate the cross section of the whipstock at different points and its relation to the liner around which it fits, and showing further by dotted outline the location of the bit as it passes the planes of the sectional views.

In completing a well it is customary to land a casing 1, then drill into the producing formation through the lower end of the casing, forming a bore 2 of smaller diameter than the well bore in which the casing sets. A liner 3 is then lowered through the casing and into the bore 2. The upper end of the liner is usually provided with a collar 4, or if it is desired to suspend the liner from the casing, various types of conventional liner hangers are used, some of which are constructed so as to be drillable.

The liner 3 in the present instance and the collar 4 are preferably constructed of drillable material such as aluminum or magnesium alloy. Often such drillable liners are intended for only temporary use.

Our invention consists essentially of a sleeve 11 which is welded or formed integrally with a collar 12 which connects two sections of the drillable

liner 3. The sleeve 11 is beveled on one side to form a whipstocking face 13. The sleeve, particularly the whipstocking face, is hardened.

When utilizing the whipstock a drill string with a suitable bit is lowered and the collar, as well as the upper portion of the temporary or drillable liner 3, is drilled up by the bit. When the bit encounters the sleeve, or whipstock 11, it is deflected in the direction of the whipstocking face 13. 10. Inasmuch as the whipstocking face actually is an elongated hollow lip, and the wearing edges are necessarily limited in thickness, the corners of these edges are beveled away from the angle of contact of the bit, as indicated by 14, in the several cross sectional views. It is intended, of course, that care be taken in utilizing our whipstock sleeve so that the edges forming the whipstocking face will not be unduly damaged.

In some instances it is preferable to fill the liner with cement before commencing sidetracking operations, thus increasing the support of the whipstocking sleeve. The cement 15 may be introduced both within the sleeve and around the outside thereof, inasmuch as the liner is perforated below the whipstock and circulation may readily be established.

Inasmuch as the operating face of the whipstock is the beveled edge of the sleeve the point of contact with the drilling bit varies, and the 30 whipstocking sleeve, as viewed from the side, is somewhat convex rather than straight. However, the deflecting angle is constant. This is best indicated by comparison of the several cross sectional views.

35. If desired, the liner below the whipstocking sleeve may be conventional, that is, formed of steel, in which case only that section of the liner contained within the sleeve and extending into the casing is made of drillable material.

40. Various changes and alternate arrangements may be made within the scope of the appended claims, in which it is our intention to claim all novelty inherent in the invention as broadly as the prior art permits.

45. We claim:

1. A combination with a drillable liner, of: a sleeve formed of relatively non-drillable material surrounding said liner, said sleeve having a beveled deflecting side.

50. 2. A liner adapted to be set in an oil well below the well casing, said liner including a drillable section with its upper end extending into said casing and a sleeve of relatively harder material surrounding said drillable section, said sleeve having a beveled deflection side.
